SLIDE TRAY

Thomas M. Steinbach, Park Ridge, and Robert M. Simenelli, Des Plaines, Ill., assignors to GAF Corporation, New York, N.Y., a corporation of Delaware

Filed Feb. 20, 1968, Ser. No. 10,656

Term of patent 14 years

Int. Cl. D16—07

U.S. Cl. D61—1

FIG. 1.

FIG. 2.

FIG. 3

FIG. 4

FIG. 1 is a top plan view of a slide tray embodying our new design;

FIG. 2 is a side elevational view thereof;

FIG. 3 is a bottom plan view thereof; and

FIG. 4 is a fragmentary cross-sectional view thereof.

We claim:

The ornamental design for a slide tray, substantially as shown.
